ENGINE STARTER DRIVE

Clinton S. Janes, Elmira, N. Y., assignor, by
mesne assignments, to Bendix Aviation Corpora-
tion, South Bend, Ind., a corporation of Del-
aware

Application November 13, 1936, Serial No. 110,749

12 Claims. (Cl. 74—7)

This invention relates to an engine starter drive and more particularly to a transmission of the type which automatically connects a starting motor to an engine upon energization of the motor, and disconnects the same after the engine has become self-operative.

Starter drives of conventional type which are disengaged by the overrunning of the drive pinion when the engine starts are subject to the condition that if the engine should stall after the pinion is demeshed by the initial explosions, it is necessary to deenergize the starting motor and allow it to decelerate in order to secure reengagement of the pinion and resumption of the cranking operation by reenergizing the starting motor.

In some cases, especially when this condition of "false starting" is prevalent and persistent, it is preferred to utilize a form of transmission which is not disengaged by the initial explosions of the engine, but merely overruns and resumes cranking as soon as the engine slows down to a speed corresponding to that of the starting motor.

It is an object of the present invention to provide a novel engine starter drive of the automatic mesh and demesh type, in which the engagement of the parts is maintained irrespective of false starts or abortive explosions of the engine.

It is a further object to provide such a device in which engagement of the drive is maintained during acceleration of the starting motor, irrespective of acceleration of the engine member due to self-operation thereof.

It is another object to provide such a device in which the pinion is permitted to overrun the starting motor during periods of rapid acceleration of the engine member, while remaining in meshed relation with the engine member.

It is another object to provide such a device in which meshing of the drive is accomplished by acceleration of the starting motor, and demeshing is controlled mainly by deceleration thereof.

It is a further object to provide such a device embodying automatic braking means for the starting motor when it is deenergized.

It is another object to provide such a device embodying novel provisions for indexing the pinion into proper position for meshing with the engine member in case of tooth abutment therewith during the meshing operation.

Further objects and advantages will be apparent from the following description taken in con-

nnection with the accompanying drawings in which:

Fig. 1 shows a side elevation partly in section of a preferred embodiment of the invention;

Fig. 2 is a similar view showing the parts in driving position;

Fig. 3 is a similar view showing the parts in the positions assumed during overrunning of the engine member while the drive pinion is in engagement therewith;

Fig. 4 is a section taken substantially on the line 4—4 of Fig. 1;

Fig. 5 is a view similar to Fig. 1 showing the parts in the positions assumed in case during the meshing operation a tooth of the pinion abuts against a tooth of the engine member;

Fig. 6 is an expanded detail in perspective of the traversing nut and barrel members;

Fig. 7 is an expanded view in perspective of the pinion and its associated parts including the screw and nut member;

Fig. 8 is a side elevation partly in section of a second embodiment of the present invention;

Fig. 9 is a similar view showing the parts in driving position;

Fig. 10 is a similar view showing the parts in the positions assumed during overrunning of the engine member;

Fig. 11 is a section taken substantially on the line 11—11 of Fig. 8;

Fig. 12 is a view similar to Fig. 8 showing the parts in the positions assumed in case of tooth abutment between the pinion and engine member;

Fig. 13 is an expanded detail in perspective showing the barrel and traversing pinion, the barrel being broken away for the sake of clarity; and

Fig. 14 is a similar view of the pinion and its associated parts.

Referring first to Fig. 1 of the drawings, there is illustrated a power shaft 1 which may be the extended armature shaft of a starting motor.

A sleeve 2 incorporating a driving head 3 is fixed to the power shaft in any suitable manner as indicated at 4 and 5, and has slidably mounted thereon a screw shaft 6 incorporating a driven head 7 in spaced relation to the driving head 3.

A pair of anchor members 8 and 9 in the form of spirally shaped discs are non-rotatably mounted on the driving and driven heads respectively and are provided with openings 11 and 12 (Figs.

4 and 2) adapted to receive the outturned ends 13 and 14 of a drive spring 15 which thereby con-

10

ncts the driving and driven heads to drive the screw shaft 6 yieldably from the power shaft 1.

A pinion 16 is slidably and rotatably mounted on the power shaft 1 beyond the end of the sleeve 2 in position to be moved longitudinally into and out of engagement with a member such as a flywheel gear 17 of an engine to be started. Means are provided for actuating the pinion from the screw shaft 6 comprising an inertia and transmission member in the form of a barrel 18 having a threaded connection with the screw shaft and also having a second threaded connection with the pinion. The threaded connection between the barrel and the screw shaft 6 is formed by a nut 19 rigidly fixed in one end of the barrel 18 as by means of radial projections 21 on the nut located in slots 22 of the barrel and retained therein by means such as a split thrust ring 23.

The threaded connection between the barrel and pinion comprises a nut member 24 having radial projections 25 located in the slots 22 of the barrel and held against longitudinal movement in the barrel by engagement against the shoulders 26 at the ends of the slots 22 on one side, and by the spacing and reenforcing cylinder member 27 surrounding the middle portion of the barrel 18 and spacing the nut members 21 and 25 in the barrel.

A screw member 28 is fixed to the pinion in any suitable manner as by means of splines 29 (Fig. 7) in the screw member engaging in the spaces 31 between the extended portions of the teeth 32 of the pinion. A thrust ring 33 is located on the pinion back of the screw member 28, and the parts are retained in assembled position by suitable means such as a bushing 34 having a shoulder 35 abutting against the ends of the splines 29 and being spun outwardly into the flared portion 36 of the pinion as indicated at 37 in Fig. 1 in order to clamp the parts together. It will be noted that the screw member 28 is provided with a smooth portion 38 (Fig. 7) on which the nut 24 rests when the parts are in idle position whereby the pinion is free to overrun the nut member 24.

A stop nut 39 is fixed on the end of the sleeve 2 beyond the screw shaft 6, and a thrust disc 41 is interposed between the end of the screw shaft 6 and the stop nut. A thrust ring 42 is loosely mounted on the screw shaft to limit the travel of the nut 19 to the left with respect to the sleeve 2, whereby further travel of the nut 19 on the screw shaft 6 after engagement with the thrust ring 42 causes the screw shaft 6 to move to the right and compress the drive spring 15 as illustrated in Fig. 2.

Means for yieldably maintaining the nut 19 in idle position is provided in the form of an anti-drift spring 43 located between said nut and a flange 44 on the periphery of the thrust disc 41. The screw shaft 6 is preferably provided with a smooth portion 45 at the idle position of the nut 19 so as to permit said nut with the barrel 18 and its associated parts to overrun the screw shaft when the latter is accelerated.

Means are provided for insuring initial entry of the nut 19 into the threads of the screw shaft 6 in the form of a reentry spring 46 located between the nut 24 and the flange 44 of the thrust disc 41, and means for insuring reentry of the nut 24 in the threads of the screw member 28 is provided in the form of a spring member 47 (Fig. 7) located between the nut 24 and the thrust ring 33.

In the operation of this embodiment of the invention, starting with the parts in the positions illustrated in Fig. 1, rotation of the power shaft 1 when the starting motor is energized causes the screw shaft 6 to rotate therewith by virtue of the driving connection through the drive spring 15. Inasmuch as the barrel 18 and its associated members, due to their inertia, do not immediately partake of this rotation, they are traversed by the threaded action of the nut 19 on the screw shaft 6 until said nut engages the thrust ring 42, at which time the pinion 16 is placed in initial engagement with the engine gear 17 as illustrated in Fig. 3. Since the further threaded action of the nut 19 on the screw shaft 6 is resisted by the compression of the drive spring 15, the barrel 18 is caused to rotate, and since the pinion 16 is prevented from rotation by its engagement with the engine gear 17, the pinion is projected into full mesh with the flywheel gear by the threaded engagement between the nut 24 and screw member 28 as illustrated in Fig. 2. When the pinion 16 has reached the end of its traversal in the barrel 18 as defined by the engagement of the thrust ring 33 with the shoulder 48 on the end of the barrel, the pinion is forced to take up the rotation of the barrel and consequently transmits this rotation to the engine gear 17. The compression of drive spring 15 by the backward movement of screw shaft 6 is limited by the abutment of the driving and driven heads 3 and 7, between which a thrust washer 49 is preferably interposed.

When the engine becomes self-operative by reason of one or more explosions in the cylinders 35 thereof, the pinion 16 is threaded back within the barrel 18, as illustrated in Fig. 3, until the screw member 28 runs out of the nut 24, whereupon the pinion is permitted to overrun freely as long as it is driven by the engine gear faster than the rotation of the barrel. It will be noted, however, that the pinion 16 remains in engagement with the flywheel 17 so that if the engine does not continue to fire, the pinion will be again moved into full engagement with the engine gear 17 and cranking will be resumed as soon as the flywheel gear slows down to a speed corresponding with that of the power shaft 1. This "toe hold" of the pinion in the engine gear while it is overrunning the barrel, is maintained by reason of the fact that the starting motor is rapidly accelerating due to the temporary relief of the cranking load, so that the barrel is firmly held by its rotative inertia in its fully traversed position as shown in Fig. 3.

When a true start of the engine is secured and it continues to be self-operative, deenergization of the starting motor due to the opening of its cranking circuit by the operator or by a suitable automatic starter control, causes the starting motor to decelerate quite rapidly due to the friction of its parts. This deceleration, by reason of the momentum of the barrel and its associated parts, in conjunction with the effect of the anti-drift spring 43 and the rotative drag of the screw member 28 as it overruns the barrel, causes the barrel to overrun the decelerating screw shaft 6 and be traversed by the nut 19 back to idle position where it will rotate freely on the smooth portion 45 of the screw shaft 6 until the parts come to rest.

It will be readily appreciated that the inertia of the barrel and its associated parts is quite large due to the concentration of their weight near the periphery thereof. If it should be deemed de-

sirable to still further increase the momentum of those parts, it may readily be done in any suitable way as by increasing the thickness of the barrel 18 or of the cylinder 27.

Means are preferably provided for yieldably maintaining the pinion 16 in its idle position in the form of an anti-drift spring 50 therefor.

If, during the meshing operation, the teeth of the pinion 16 should abut against the ends of the teeth of the flywheel gear as illustrated in Fig. 5, traversal of the barrel is resisted by this abutment. The screw shaft 6 is thus forced back, compressing the drive spring 15, thus causing the progressive tightening of the threaded engagement between the nut and screw shaft and transmission of torque to the barrel to index the pinion. The frictional engagement between the nut 24 and the thrust ring 33 on the pinion is ordinarily sufficient to transmit this torque to index the pinion, but if this purely frictional engagement between the nut and thrust ring be found insufficient under some circumstances, it may be preferred to form serrations or other positive clutching means upon these elements to transmit the indexing torque as illustrated at 51 and 52. It will be noted, of course, that the reentry spring 47 maintains these serrations out of engagement during the over-running of the pinion.

The embodiment of the invention illustrated in Figs. 8 to 14 inclusive differs from that previously described mainly in the novel form of indexing means provided for insuring proper mesh of the starting pinion with the engine member. As illustrated in Fig. 8, a power shaft 61 has a sleeve 62 suitably fixed thereon, which sleeve carries a screw shaft 63 driven from the sleeve by means of a drive spring 64, all as previously described except that the drive spring 64 is close wound without the spaces between the convolutions provided in the drive spring 15 of the first embodiment, and the longitudinal motion of the screw shaft 63 is limited to only that sufficient to close the clutch formed by the opposing surfaces of the drive head 65 and driven head 66 against the interposed thrust washer 67.

A pinion 68 is freely mounted on the power shaft 61 in position to move into and out of engagement with an engine gear 69, and has fixed thereto a screw member 71 threaded into the end of a barrel member 72 and suitably retained therein as by means of a split thrust ring 73 in the end of the barrel. This thrust ring is seated in a circular groove adjacent the end of the barrel, and may, if desired, be further held in place by spinning over the end of the barrel as shown in Figs. 12 and 13. The barrel is provided with a smooth portion 74 adjacent the threaded portion which permits the screw member 71 to run off the ends of the threads and overrun freely.

Means for driving the barrel from the screw shaft 63 is provided in the form of a nut 75 anchored in the end of the barrel opposite from the pinion, and arranged to engage the threads of the screw shaft although normally resting on the smooth portion 76 thereof.

A stop nut 77 is fixed on the end of the sleeve 62 and limits longitudinal motion of the screw shaft 63 thereon by means of an interposed thrust disc 78 which also serves to limit the longitudinal motion of the nut 75 and accordingly of the barrel 72 in the direction to mesh the pinion.

Means are provided for normally maintaining the nut 75 in idle position in the form of an anti-drift spring 79 bearing against said nut and the

thrust disc 78. A reentry spring 81 located between the thrust disc 78 and a split thrust ring 82 mounted in the interior of the barrel 72, yieldably maintains the nut 75 in position to enter the threads of the screw shaft 63. A second positioning spring 83 located between the screw member 71 and the thrust ring 82 yieldably urges the screw member 71 into initial engagement with the threads in the interior of the barrel 72 during overrunning of the pinion as illustrated in Fig. 10.

In this embodiment of the invention, the pinion 68, when in normal position as illustrated in Fig. 8, is protruded from the barrel to its maximum extent. This is accomplished, as there illustrated, by extending the stop nut 77 by the formation thereon of a conical clutch element 84 arranged to engage in a conical seat 85 formed in the end of the pinion bushing 86. During the demeshing of the drive, the extension 84 of the stop nut limits the traversal of the pinion which is thus retarded with respect to the barrel, causing the pinion to thread itself out of the barrel to its idle or extended position shown in Fig. 8. The positioning spring 83 assists this action and yieldably maintains the pinion in its extended position.

In the operation of this embodiment of the invention, rotation of the power shaft 61 transmitted through the drive spring 64 to the screw shaft 63 causes the nut 75 to be traversed along the screw shaft into engagement with the thrust member 78, thus moving the pinion 68 into driving engagement with the engine gear 69 as illustrated in Fig. 9. Further rotation of the power shaft causes the pinion to be rotated to crank the engine. When the engine starts, the acceleration of the flywheel gear causes the pinion 68 to overrun the barrel 72, whereby the pinion withdraws into the barrel until it runs off the ends of the threads in the barrel. Thereafter the pinion overruns freely while maintaining its engagement with the engine gear as shown in Fig. 10; since the barrel 72 is firmly held in its operative position by the acceleration of the starting motor due to the release of the cranking load thereon. If the engine fails to continue in operation, the pinion will be moved back into driving engagement therewith by the threaded engagement between the screw member 71 and the barrel 72, whereupon cranking will be resumed until a true start is secured. Thereupon deenergization of the starting motor and consequent deceleration of the power shaft 61 cooperates with the spring 79 and the overrunning drag of the pinion to cause the barrel 72 to be traversed back to idle position where it will overrun the screw shaft until the momentum of the parts is dissipated. During this return movement of the barrel 72, the pinion 68 is threaded out to its normal position by the cooperation of the clutching surfaces 84 and 85 in conjunction with the action of the spring 83 as above set forth.

If, during the meshing operation of this embodiment of the invention, tooth abutment should occur between the pinion 68 and engine gear 69, the longitudinal movement of the pinion 68 will be temporarily arrested, whereupon the threaded connection between the pinion and barrel is effective by reason of the continued longitudinal movement of the barrel to index the pinion into proper registry with the flywheel teeth, whereupon the expansion of the spring 83 will insure proper engagement of the pinion and engine gear teeth. It will be understood that the pitch of the threads of the barrel 72 and pin-

ion screw member 71 is sufficiently steep to secure effective mesh-enforcing action thereof, while readily permitting the overrunning action of the pinion when the engine fires.

5 It is to be understood that the formation of the threads integrally with the barrel is merely an optional arrangement permitting a reduction in the diameter of the barrel, and that the threads may be formed on a separate nut member such as illustrated at 24 in the first embodiment of the invention, if so desired.

10 In connection with either of the embodiments of the invention illustrated, it may, under some circumstances, be desirable to provide automatic means for increasing the rate of deceleration of the starting motor when it is deenergized in order to more positively control the demeshing action of the barrel 18 or 72. One form of such means is illustrated in Figs. 8 and 12 in the form 15 of a brake cylinder 81 surrounding the drive spring 64 in frictional engagement therewith and prevented from rotation by being mounted on any suitable fixed support such as the frame of the starting motor 88. It will be readily appreciated that during the transmission of torque 20 from the power shaft 61 to the screw shaft 63, the drive spring 64 will be wound up by the torque exerted whereby its diameter will be decreased and the friction between the periphery 25 of the spring and the brake member will be relieved. However, when the starting motor is deenergized and the screw shaft with its associated parts tends to overrun the starting motor, the spring will be expanded into frictional engagement 30 with the brake cylinder, thus causing rapid deceleration of the starting motor and drive.

35 Although but two embodiments of the invention have been shown and described in detail, it will be understood that various changes may be made in the forms and arrangements of the parts, and that certain features may be used 40 optionally and interchangeably without departing from the spirit of the invention as defined in the claims appended hereto.

45 What is claimed is:

1. In a starter drive for internal combustion engines, a power shaft, a pinion mounted thereon for movement into and out of engagement with a member of an engine to be started, and means responsive to acceleration of the power shaft for moving the pinion into driving engagement with the engine member and thereafter transmitting rotation thereto, said means including means responsive to self-operation of the engine for causing the pinion to overrun the power shaft while remaining in engagement with the engine member, and said first-named means further including means responsive to deceleration of the power shaft for moving the pinion out of engagement with the engine member and returning it to idle position.

50 2. In an engine starter drive, a power shaft, a barrel member threaded thereon, a stop member limiting longitudinal movement of the barrel on the shaft, and a pinion threaded in the barrel and movable thereby into and out of engagement with a member of an engine to be started, said pinion being arranged to run off its threaded connection with the barrel upon acceleration of the engine member, without disengaging from the engine member.

55 3. In an engine starter drive, a power shaft, a barrel member threaded thereon, a stop member limiting longitudinal movement of the barrel

on the shaft, a pinion threaded in the barrel, normally projecting therefrom, and movable thereby into and out of engagement with a member of an engine to be started, said pinion being arranged to telescope into the barrel and run off the threaded connection therewith responsive to acceleration of the engine member, and means for reengaging the threaded connection of the pinion in the barrel and causing the pinion to project from the barrel when the barrel returns to idle position.

60 4. In an engine starter drive, a power shaft, a barrel member having a threaded connection therewith for longitudinal movement with respect thereto and rotary movement thereof and therewith, and an engine driving member mounted in said barrel projecting therefrom and movable therewith into and out of engagement with a member of an engine to be started, said driving member and barrel having an inclined connection operative in case of tooth abutment of the driving member and engine member to index the driving member into proper meshing position.

65 5. In an engine starter drive, a power shaft, a pinion, means actuated upon acceleration of the power shaft to move the pinion into engagement with a member of an engine to be started and thereafter rotate the pinion, and actuated upon deceleration of the power shaft to return the pinion to idle position, and means operative upon 70 abutment of the pinion with the engine member to index the pinion, said last means also serving to move the pinion into position to overrun the power shaft while remaining in operative engagement with the engine member when the engine starts.

75 6. In an engine starter drive, a starting motor, a shaft driven thereby, a pinion mounted on said shaft for longitudinal movement into and out of engagement with a member of an engine to be started, means responsive to acceleration of said shaft for moving the pinion into driving engagement and maintaining said engagement irrespective of self-operation of the engine, and responsive to deceleration of the shaft for moving the pinion out of driving engagement, and normally operative braking means for said shaft including an element of the moving means rotatable with said shaft, and a fixed braking element normally in engagement therewith but disengaged therefrom during energization of the starting motor.

80 7. In an engine starter drive, a starting motor, a shaft driven thereby, a pinion mounted on said shaft for longitudinal movement into and out of engagement with a member of an engine to be started, means responsive to acceleration of said shaft for moving the pinion into driving engagement and maintaining said engagement irrespective of self-operation of the engine, and responsive to deceleration of the shaft for moving the pinion out of driving engagement, and braking means for said shaft including an element of the moving means rotatable with said shaft, and a fixed braking element disengaged therefrom while the starting motor actuates the drive, but engaged thereby when the starting motor is deenergized and the drive tends to overrun the starting motor.

85 8. In an engine starter drive, a power shaft, a pinion, and means for operating the pinion from the power shaft including two inclined connections in series, both connections cooperating to automatically traverse the pinion into and out of driving engagement with a member of the engine to be started, one connection including discon-

necting means operative upon acceleration of the engine member to cause the pinion to overrun the power shaft while being maintained in co-operative relation therewith, and the other connection including an inertia member operative upon deceleration of the drive shaft to move the pinion to inoperative position.

9. In an engine starter drive, a power shaft, a pinion, an inertia member, an overrunning connection between the power shaft and inertia member, and an overrunning connection between the inertia member and pinion, said first overrunning connection including means responsive to acceleration and deceleration of the power shaft to move the pinion into and out of mesh with a member of an engine to be started.

10. In an engine starter drive, a power shaft, a pinion, an inertia member, an overrunning connection between the power shaft and inertia member, and an overrunning connection between the inertia member and pinion, said first overrunning connection including means responsive to acceleration and deceleration of the power shaft to move the pinion into and out of mesh with a member of an engine to be started, said second overrunning connection including means for indexing the pinion in case the meshing movement of the pinion is obstructed.

11. In an engine starter drive, a power shaft, a screw shaft, a driving connection therebetween, a barrel member having a threaded connection

with the screw shaft, stop means limiting longitudinal movement of the barrel on the shaft screw, and a pinion slidably mounted on said power shaft, said pinion and barrel having interengaging means forming an inclined connection therebetween, the pinion being movable by the barrel into and out of engagement with a member of the engine to be started, said interengaging means being so formed that they disengage so that the pinion overruns the barrel responsive to self-operation of the engine, and said threaded connection being so dimensioned that the barrel runs off the end of the threads and overruns the screw shaft, responsive to deceleration of said screw shaft.

12. In an engine starter drive, a power shaft, a barrel member threaded thereon, a stop member limiting longitudinal movement of the barrel on the shaft, a pinion threaded in the barrel and movable thereby into and out of engagement with a member of an engine to be started, and means in the barrel limiting longitudinal movement of the pinion with respect thereto, the threaded connections between the shaft and barrel and between the barrel and pinion terminating adjacent the positions said parts assume when the pinion is out of engagement with the engine member, so as to form overrunning connections therebetween.

CLINTON S. JANES. 30
